HOSE SUPPORTER

Charles C. Platt, New York, N. Y.

Application May 28, 1931, Serial No. 540,603

1 Claim. (Cl. 241—5)

While the hose and supporters of the present invention are capable of usefulness independently of each other, they are peculiarly adapted and especially designed for intimate coaction to the 5 end that a comfortably supported hose may be provided.

Insofar as the hose structure is concerned, an object of the invention is to provide a sock or stocking which will not only assure comfort in use 10 but which will protect the flesh from contact with a hose supporter, and to the extent that the stocking, sock or other leg covering element is capable of absorbing perspiration, will protect the elastic material of the garter element from 15 deterioration in the ordinary course of use.

Insofar as the supporter element is concerned, the device combines the comfort of an ordinary golf garter with the security of the conventional 20 sock garter and while capable of the convenient application which is characteristic of the golf 25 hose supporter, is not dependent merely upon the tautness of the band for its effectiveness in supporting the leg covering with which it is associated. The sock and the garter in combination, assure not only comfort and protection to the 30 wearer, but the double security afforded by the combination of an elastic leg gripping band with means for mechanically interengaging with the 35 stocking.

It is among the objects of the present invention to provide a hose and garter assemblage of this character, which will be of simple, rugged, durable construction, well suited to meet the requirements of economical manufacture and expeditious 40 facile manipulation when the sock and garter are donned or removed.

Another object is to provide a hose supporter, conveniently adjustable to the requirements of the user and acting automatically to mechanically 45 engage the stocking which it supports, merely as an incident of closing a single clasp or other separable fastener element.

Other objects are to provide an arrangement in which the supporter does not become soiled, because it never actually contacts the flesh, and an arrangement which will present an unusually 50 neat and stylish appearance when the hose and garter are worn together.

In accordance with a preferred embodiment of the invention, the hose are designed to embrace and cover the calf of the wearer. Unlike conventional socks in which foot lengths are designed independently of the width or length of the leg encircling portion, each size of hose maintains the 55 same ratio of leg length and width to the foot size.

It will thus be more or less self-evident that unlike conventional socks, the user of a large size hose who usually has large legs as well as feet, will not be discommoded by an embarrassingly short leg length.

The garter which is adapted when used with the sock of the present invention, to encircle the same, slightly above the bulge of the calf of the leg, has its normal elastic action supplemented by the use of gripper elements, which gently, but firmly bite into the fabric of the sock and afford double security against slippage without injury to the leg.

The invention may be more fully understood from the following description in connection with the accompanying drawing, wherein

Fig. 1 is a perspective view showing a sock and garter embodying the present invention, in applied position;

Fig. 2 is an enlarged perspective view of the garter;

Fig. 3 is a further enlarged transverse sectional view on the line 3—3 of Fig. 2, and

Fig. 4 is a view taken on the same scale as Fig. 3 but showing an inside face view of one of the 25 adjustable gripper elements.

Referring with particularity to the drawing, I have used the reference numeral 10 to designate generally a circular adjustable hose supporter adapted to encircle the leg of the wearer just 30 above the bulge of the calf. This supporter is shown in position to grip and hold a stocking or sock 11.

The latter may be of conventional structure, save that the leg lengths and widths are proportioned to the foot sizes thereof in direct contradistinction to the conventional practice of using a single leg length and width with all foot sizes. Obviously such practice has resulted in the wearers of the larger-sized hose being unnecessarily embarrassed by the fact that the hose were entirely too short, particularly where the wearer was possessed of a stout ankle and calf and that it was difficult to adjust and support them by standard garter constructions and that the small leg widths caused uncomfortable binding of the leg.

The garter is formed of a length of woven elastic tape. One end 12 of the tape carries the keeper element 13 of a separable clasp. The other end of the tape is looped back upon itself to form an adjustable bight 14. The running end of the bight passes through a conventional slip buckle 15 and the standing end of the bight is anchored to the slip buckle. Slidably mounted

on the bight is the hook element 13a of the separable fastener.

Garters of this general type are known to the art but in accordance with the present invention, 5 I provide them with supplemental means designed to mechanically engage the fabric of the sock or stocking to be supported, such means comprising a pair of identical slide elements indicated generally at 16, 16. One of these devices is mounted

10 on the free end 12 of the hose supporter and the other is mounted upon the inner run of the bight 14.

Each slide may comprise a small metal plate having its ends hooked rearwardly at 17 to engage and embrace the elastic 10 which resiliently grips the elastically knitted top of the hose. Each plate has provided on the face thereof, a plurality of outstruck hose engaging elements 18 of any suitable character. The hose engaging portions 15 which are struck from the flat inner faces of the plates 16 may comprise small projections, but they are preferably formed by punching holes completely through the plates so that the outwardly struck hose-engaging devices are separated by the punching operation, into a plurality of converging pointed tongues or spurs (illustratively three), the sharp points and the comparatively sharp toothed edges of which are peculiarly adapted for snagging engagement with the knit 20 fabric of the upper portion of the sock.

The projections are of insufficient height to pass through the knit fabric of the stocking and injure the calf of the leg, it being understood that they need merely be high enough to bite into the stocking, inasmuch as they will engage the stocking at the top portion where there is usually ribbed knitting. There is no danger of the production of runs in the hose by the use of the supporter.

30 40 In order to facilitate the sliding of the gripper

members along the elastic tape, which constitutes the supporter, it will be apparent that by simply stretching this tape, its effective width is reduced and sliding of the sock engaging elements may be rapidly and conveniently effected.

It will thus be seen that there are herein described garments and combinations thereof in which the several features of the invention are embodied and which in their action attain the various objects of the invention and are well suited to meet the requirements of practical use.

As many changes could be made in the above described construction and many apparently widely different embodiments of the invention could be made without departing from the scope 15 thereof, it is intended that all matter contained in the above description or shown in the accompanying drawing, shall be interpreted as illustrative and not in a limiting sense.

Having thus described my invention, what I 20 claim as new and desire to secure by Letters Patent is:—

A garter including a strip of elastic material adapted to encircle a stocking, a plurality of unslotted plate members extending transversely of the strip and narrower than the width of the strip, the ends of the plates being bent over the edges of the strip to define channels, the faces of the plates lying interiorly of the strip, means pressed outwardly from the face of the plates to 30 engage a hose encircled by the strip, the opposite faces of said plates being smooth and cooperating with the turned back ends to afford ready sliding of the plates along the strip said supporter including an adjustable bight at one end and separable clasp elements carried by the bight and by the opposite end of the strip, the side plates being mounted respectively on the inner run of the bight and on the unlooped end of the strip.

CHARLES C. PLATT. 40
